PAPER BAG

Harold V. Kindseth, Minneapolis, Minn., assignor
to Bemis Bro. Bag Co., Minneapolis, Minn., a
corporation of Missouri

Application March 10, 1938, Serial No. 195,083

1 Claim. (Cl. 229—62)

This invention relates to new and useful improvements in paper bags of the general type usually employed for packaging finely comminuted material such, for example, as sugar, flour, corn meal, breakfast foods, and various other commodities.

In the operation of folding the walls of a bag mouth into closing and sealing relation, it is sometimes difficult to make the closed bag tops uniform in appearance, because of the inherent nature of the paper. The walls of the empty bags are usually folded into flatwise relation before the bags are filled, to facilitate stacking the empty bags, one upon another. Such folding and stacking of the empty bags may cause one or more vertical folds to be made in the walls of the bag. These folds may interfere somewhat with the folding of the bag top walls into closing relation, whereby it is frequently difficult to close the bag tops in such a manner that all tops will be uniform and neat in appearance. It is therefore desirable that means be embodied in the construction of the bag walls, whereby they may readily and expeditiously be folded into closing relation with the assurance that all of the closed bag tops will be uniform and substantially alike in appearance.

An object of the present invention therefore is to provide a bag having means embodied in the construction of its walls to facilitate folding the bag mouth walls into sealing relation, whereby all of the sealed bag tops will be uniform and symmetrical, and neat in appearance.

A further object is to crimp or otherwise treat a portion of one or more of the walls of the bag mouth in the region of the level of the contents of the bag, whereby when said walls are folded inwardly over the material in the bag, the transverse folds provided therein will be substantially at right angles to the vertical axis of the bag body, whereby all of the closed bag tops will be uniform and substantially alike in appearance, and whereby the perimeter of the closed bag top will be symmetrical about the median plane of the bag body.

A further and more specific object of the invention is to horizontally crimp or score an area of one or more of the bag top walls at the point whereby they are bent or folded, when closing the bag top, thereby to more sharply define the perimeter of the bag top and whereby the sealed tops will be uniform and substantially alike in appearance.

Other objects of the invention will appear from the following description and accompanying

drawing and will be pointed out in the annexed claim.

In the accompanying drawing, there has been disclosed a structure designed to carry out the various objects of the invention, but it is to be understood that the invention is not confined to the exact features shown as various changes may be made within the scope of the claim which follows.

In the drawing:

Figure 1 is a perspective view of an empty bag showing the invention embodied in a wall thereof;

Figure 2 is a view showing a filled bag prior to having its open top closed;

Figure 3 is a view showing one of the bag mouth walls folded inwardly over the contents of the bag;

Figure 4 shows the next operation of closing the bag top, wherein it will be noted that the opposite end wall is folded inwardly over the first folded wall;

Figure 5 is a top view of Figure 4, showing gum applied to the laterally projecting flaps of the partially closed top;

Figure 6 shows the bag top after it has been completely closed and sealed;

Figure 7 is an enlarged detail sectional view on the line 7—7 of Figure 2, showing how a portion of the paper is crimped or treated to facilitate bending or folding the bag mouth walls into closing and sealing relation;

Figure 8 is a view showing both of the end walls of the bag horizontally crimped to facilitate folding;

Figure 9 is a view showing the opposite side walls of the bag crimped; and

Figure 10 is a view showing the horizontal crimping of the bag walls extending completely around the circumference of the bag.

In the selected embodiment of the invention here shown, there is illustrated in Figure 1, a bag of more or less conventional design, commonly known to the trade as a "flat bag," and comprising a body portion 2 provided with a suitable bottom 3. The bag, when empty, usually has its walls folded into flatwise relation, whereby a vertical fold 4 is provided at each side of the folded bag, as will be understood by reference to Figure 4.

When the empty bag is expanded, or opened up and has received a charge of material, as shown in Figure 2, the bag mouth is defined by end walls 5 and 6 and side walls 7 and 8. The bag shown in the drawing is of rectangular cross-section, as best shown in Figure 6, but it is to be

understood that the invention may be applied to bags of other shapes, where applicable, without departing from the scope of the invention.

To close the mouth of a bag of the type herein disclosed, the bag mouth walls are preferably folded inwardly over the bag body and united by a suitable gum, as shown in Figure 6. To accomplish this, the end wall 5 is first folded inwardly over the contents of the bag by suitable means such, for example, as indicated by the numeral 9, in Figures 3 and 4. By thus inwardly folding the end wall 5 and outwardly extending the side walls 7 and 8, the end wall 6 is folded inwardly over the end wall 5, as best shown in Figure 4 and at the same time, oppositely extending flaps 10 are provided, as shown in Figure 5. The flaps 10 are then folded inwardly over the previously folded end walls, one over the other, as shown in Figure 6, whereby the operation of closing and sealing the bag mouth is completed. It is to be understood that portions of the bag top walls are suitably gummed, as indicated at 11 and 12 in Figures 3 and 5, to prevent the folded bag top walls from unfolding.

When the bag mouth walls have been folded into closing relation, as above described and as best illustrated in Figure 6, the perimeter of the bag top is defined by the horizontally disposed corners *a—a* and *b—b*, which must be properly disposed with respect to one another to provide a neat appearing bag top. In other words, the corners *a—a* must be parallel, and, in like manner, the corners *b—b* must be substantially parallel. The corners *a—a* and *b—b* must also be disposed in right angular relation in order that the perimeter of the closed bag top will be symmetrical about the median plane of the bag body.

I have found from actual experience, that the vertical folds 4 in the bag walls, and also the conventional vertical ribbing or scoring of the bag walls, not shown, frequently causes the paper to fold along lines which are not parallel, or symmetrically arranged with respect to the median plane of the bag body, whereby the completed bag top may become distorted and unsightly in appearance.

To overcome this difficulty, I have found that by crimping one or more of the walls of the bag mouth in the region of the level of the contents of the bag, as generally indicated by the numeral 14 in Figures 1, 2, 4, and 6, the objectionable feature, above referred to, is completely eliminated.

In Figures 1 to 6, inclusive, there is illustrated a bag having a portion of one of its walls horizontally crimped or scored at substantially the level of the contents of the bag body. This horizontal crimping of the bag mouth wall will cause said wall to fold or bend on a horizontal line,

when said end wall is folded inwardly over the bag body, as shown in Figure 4, regardless of whether the bag top walls are folded by automatic machinery, or by manually folding them into closing and sealing relation, as shown in the patents to Daniel Belcher, No. 1,868,686 and No. 1,937,506, respectively.

In Figure 8, I have shown a bag having its oppositely disposed end walls 15 and 16 horizontally crimped, as shown at 17, thereby to facilitate inwardly folding said walls so that the corners *a—a* of the closed bag top will be substantially parallel and symmetrical to the median plane of the bag body.

In Figure 9, there is shown a bag having its oppositely disposed side walls 18 and 19 horizontally crimped or scored, as indicated at 20, and in Figure 10, there is shown a bag whose upper wall portions are crimped, as shown at 21, around the entire circumference of the bag. When the walls are thus horizontally crimped or scored, the walls, when folded into closing and sealing relation, will provide a bag top whose corners *a—a* and *b—b* will be disposed in right angular formation, whereby the bag top will be symmetrical about the median plane of the bag body and will present a very neat appearance.

Crimping certain areas of the walls of the bag, as herein disclosed, adds very little to the cost of the bag and greatly facilitates the operation of folding the bag top walls into closing and sealing relation, and is an assurance that all of the closed bag tops will be uniform and symmetrical in appearance.

In the accompanying drawing, I have shown the invention applied to a bag of the "flat type," but it is to be understood that the invention may be applied to other types of bags as, for example, those commonly known as "intuck bags," whose end walls are tucked between the side walls, when the bag is empty.

I claim as my invention:

A paper bag particularly for comminuted materials, comprising a bag body composed of a plurality of walls and upper folding portions integral with said walls for closing the bag, at least a portion of a wall of the bag body and its upper folding portion having a plurality of closely spaced and parallel horizontally extending crimps defining an area of linear scores within the range of the level of the material to be packed in the bag body to facilitate the closing of the bag along one of the score lines into a uniform and neatly closed bag with the perimeter of the closed bag symmetrical about the top of the median plane of the bag body.

HAROLD V. KINDSETH.
